US00D984419S

(12) **United States Design Patent** (10) **Patent No.:** **US D984,419 S**
(45) **Date of Patent:** **** Apr. 25, 2023**

(54) **WIRELESS EARBUD SET**

(71) Applicant: **Jieqing Xiong**, Shenzhen (CN)
(72) Inventor: **Jieqing Xiong**, Shenzhen (CN)
(73) Assignee: **Shenzhen Shanzhong Technology Co., Ltd**, Shenzhen (CN)
(**) Term: **15 Years**
(21) Appl. No.: **29/784,977**
(22) Filed: **May 22, 2021**

(30) **Foreign Application Priority Data**

Nov. 24, 2020 (CN) 202030712822.9

(57) **CLAIM**

The ornamental design for a wireless earbud set, as shown and described.

DESCRIPTION

FIG. 1 is an exploded, front, top perspective view of a wireless earbud set, showing my new design;

FIG. 2 is a front, top perspective view of the case of a wireless earbud set shown separately for ease of illustration;

FIG. 3 is a rear, bottom perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is a front elevation view of the left side earbud of the wireless earbud set shown separately for ease of illustration;

FIG. 11 is a rear elevation view thereof;

FIG. 12 is a front elevation view of the right side earbud of the wireless earbud set shown separately for ease of illustration;

FIG. 13 is a rear elevation view thereof;

FIG. 14 is a right side elevation view thereof;

FIG. 15 is a left side elevation view thereof;

FIG. 16 is a top plan view thereof; and,

FIG. 17 is a bottom plan view thereof.

The broken lines depict portions of the wireless earbud set that form no part of the claimed design.
